TELEPHONE TRANSMITTER DEVICE

Sydney Brumberger, Brooklyn, N. Y.

Application July 10, 1937, Serial No. 152,896

2 Claims. (Cl. 179—138)

My invention relates to an improvement in telephone transmitter devices.

In accordance with the inventive disclosure, an instrument of this character is constructed for the purpose of receiving tone produced vibrations which through employment of the principle of operation of a microphone are accurately reproduced in the form of current variations in an electrical circuit. The electrical variations are thereafter reconverted into sound by means of a telephone receiver instrument or the like.

The primary object of the present invention is to provide a telephone transmitter device in the form of a microphone which is readily secured in a stationary operable position in association with the body or casing of the instrument.

A further object of the invention is to provide a mouthpiece member for peripherally securing the diaphragm of the microphone in position upon the casing of the device.

The invention also includes other objects, and novel features of construction and arrangement, hereinafter more particularly referred to, with the detailed description of the same in connection with the accompanying drawing.

Referring to the drawing:

Fig. 1 is a front elevation of the preferred form of the invention showing the transmitter device mounted in position on the casing of the telephone instrument.

Fig. 2 is a side elevation of the device as illustrated in Fig. 1.

Fig. 3 is a partial rear elevation of the device as shown in Figs. 1 and 2.

Fig. 4 is a partial front elevation of the telephone casing illustrating the construction of the portion of the same in which the transmitter device is secured.

Fig. 5 is a cross section taken on line 5—5, Fig. 4.

Fig. 6 is an enlarged detail front elevation view of the transmitter instrument or microphone employed in the present inventive disclosure.

Fig. 7 is a cross section on line 7—7, Fig. 6.

Fig. 8 is a front elevation of the closure member for the microphone.

Fig. 9 is a cross section on line 9—9, Fig. 8.

Fig. 10 is an enlarged detail front elevation of the mouthpiece member utilized in the present inventive disclosure, and

Fig. 11 is a cross section on line 11—11, Fig. 10.

With particular reference to Figs. 1 to 5 inclusive in the drawing, the casing upon which the telephone transmitter device is mounted is desig-

nated at 15. This casing, which is formed in any desired shape, includes therein the required devices to constitute the same a self-contained telephone instrument including a transmitter and a receiver. The receiver of the device is designated in the drawing at 16 and the transmitter at 17.

In the present disclosure which pertains to the transmitter 17, the front wall of casing 15 which is constructed to include a receiving member for 10 positioning the transmitter element thereon is indicated at 18. A separate mouthpiece member 19 forms means as hereinafter described for securing the transmitter element 17 in position.

The detail construction of the front wall of the 15 casing, Figs. 3, 4 and 5, provides that the same include a centrally open area designated in the drawing at 20. Said casing 15 further provides a circular recess at 21 against which the diaphragm element of the transmitter is secured. This 20 portion of the device forms a circumferential holding surface for the diaphragm of the transmitter device. A number of radially extending slots 22 are located in the recessed diaphragm receiving portion of the casing.

The mouthpiece member 19 is constructed to include a number of extending gripping pieces 23 which in a mounted position pass through the slots 22 in the recessed holding surface 21 and are bent against the rear surface of casing wall 30 18 to secure the same thereon as clearly indicated in Fig. 3 in the drawing.

In the transmitter proper, Figs. 6 to 9 inclusive, the diaphragm of the microphone is designated at 24. This element of the device is adapted to 35 fit into the circular recess 21 in the front wall of casing 15, the same being circumferentially secured between the casing and the mouthpiece member 19 when in a mounted position, Fig. 3.

Suitably connected to the vibration responsive 40 diaphragm 24 of the microphone is a primary electrode 25 which is spaced from the diaphragm by means of an annular insulation member 26. An insulating disc of mica or other similar substance is secured against the annular insulation 45 member 26 by the primary electrode 25. The insulating disc is designated in the drawing at 27. An open end cup 28 which is adapted to contain granular carbon particles therein as shown at 29, Fig. 3, also includes a flanged surface 30 50 which securely grips the disc 27 about the peripheral edge of the same.

A closure element 31 which includes a secondary electrode 32 is adapted to firmly fit, by friction between the contacting surfaces, over 55

the open end of the cup 28, the respective electrodes being spaced through reason of this construction in parallel relationship.

In the embodiment of the invention illustrated, a suitable source of electrical energy is provided by batteries or otherwise, not herein shown, which through wire 33, Fig. 3, and the casing of the device contacts the circumferentially mounted diaphragm element 24. The remaining portion of the electrical circuit is through the secondary electrode 32 and its contacting arm 33' which is suitably insulated from the body of the casing 15 by an insulating member such as designated at 34 in the drawing, Fig. 3. Wire 35 leading from this portion of the device is connected to a suitable telephone instrument of the receiving type such as illustrated in the drawing and designated at 16. The transmitter operates through the well-known principles of 20 microphonic effect.

Inasmuch as the inventive concepts herein disclosed may be embodied in other desired forms, various modifications of the illustrated improvements constituting the invention may occur to 25 those skilled in the art and may be made without departing from the scope and purview of the invention as herein claimed.

I claim as my invention:

1. A telephone transmitter device comprising a microphone having a diaphragm element therewith, a casing having a circular opening defined by a circumferential recessed portion thereof including a plurality of radially extending slots, the recessed surface area on the casing forming a peripheral holding surface for the diaphragm element, and a mouthpiece member, circumferentially fitting the diaphragm, having internally 5 extending gripping pieces adapted to pass through the slots in the casing to a position to secure the diaphragm element of the microphone against its holding surface.

2. A telephone transmitter device comprising a 15 microphone having a diaphragm element therewith, a casing member having an opening therein, the peripherally bounding portion of which includes a plurality of slots and forms a holding surface for the diaphragm element, and a 20 mouthpiece member including internally extending gripping pieces adapted to pass through the slots in the casing to a position to secure the diaphragm element of the microphone against its holding surface. 25

SYDNEY BRUMBERGER.
